METHOD OF AND APPARATUS FOR BURNING FUEL

Ervin G. Bailey, Easton, Pa., assignor to The Babcock & Wilcox Company, Newark, N. J., a corporation of New Jersey

Application June 24, 1936, Serial No. 86,904

14 Claims. (Cl. 116—104)

My present invention relates in general to methods of and apparatus for burning solid fuel. More particularly, my invention is concerned with an improved method of and apparatus for burning solid fuel, such as bituminous coal and analogous grades and kinds of solid fuel.

The general types of apparatus now in use for burning solid fuel are not free from objectionable characteristics. Mechanical stokers are difficult to control to maintain desirable fuel burning conditions, sensitive to any variation in the character of the fuel supplied, and not well adapted for small capacity installations such as is required for domestic service. While pulverized fuel firing has been found generally satisfactory for medium and large size furnaces, the pulverization is an item of considerable expense, and difficulties arise in removing ash from the furnace, from the depositing of dust and slag on the furnace walls and heat transfer surface, and from the presence of fly ash in the products of combustion. Moreover, a larger furnace volume is usually required for the generation of a given amount of heat with pulverized fuel firing than with gas, oil, or mechanical stokers.

In accordance with my present invention solid fuel may be efficiently burned in a relatively small combustion chamber so as to have a minimum amount of cinders and fly ash in the products of combustion and so as to facilitate the removal of incombustible solids in the fuel from the combustion chamber. In my improved process of burning solid fuel, the fuel is introduced, preferably in crushed form of sizes ranging to approximately a half inch maximum, into one end of a fuel compression and combustion chamber in which it is compressed or extruded in a tubular mass which is progressively moved towards the discharge end of the chamber. Air for combustion is supplied axially of the fuel mass in the same direction as the fuel and in a pre-heated whirling stream at a velocity and volume sufficient to maintain a high rate of combustion per unit of the exposed fuel area scrubbed by the air stream and to burn substantially all of the combustible gases evolved in the combustion chamber. The combustion chamber and air and fuel supply parts are suitably positioned and regulated to insure complete combustion of the fuel mass before the discharge end of the combustion chamber is reached. The rate of heat release in the combustion chamber is sufficient to permit the incombustible residue of the fuel to be discharged in a molten condi-

tion. The combustion chamber is arranged to discharge the high temperature heating gases into an associated heat utilizing device.

The various features of novelty which characterize my invention are pointed out with particularity in the claims annexed to and forming a part of this specification. For a better understanding of the invention, its operating advantages and specific objects attained by its use, reference should be had to the accompanying drawings and descriptive matter in which I have illustrated and described a preferred embodiment of my invention.

Of the drawings:

Fig. 1 is a sectional elevation of one form of fuel burner constructed in accordance with my invention, the plunger operating mechanism being omitted;

Fig. 2 is an enlarged end view of the apparatus shown in Fig. 1;

Fig. 3 is a plan view partly in section of the apparatus shown in Fig. 1, the hopper being omitted;

Fig. 4 is a diagrammatic view of the fuel chamber with the fuel compression means at the end of its compression stroke; and

Fig. 5 is a similar view with the fuel compression means at the beginning of its compression stroke.

In the drawings I have illustrated one form of suitable apparatus for carrying out my improved method of burning fuel comprising an elongated horizontally arranged tubular member 10 of suitable heat resistant material forming the fuel compression and combustion chamber and having a fuel inlet opening 11 formed in the upper side thereof adjacent its outer end and communicating with a fuel hopper 12 and with its inner end open and arranged to discharge through a burner port 13 formed in a wall 14 of an associated heat utilizing device. The member 10 is preferably of circular cross-section, as shown, although other cross-sectional shapes may be used. The tubular member 10 is provided on its periphery with a helical fin 15, which unites with the member and an outer tubular member 16 to form a helical passage 17 for a cooling fluid extending substantially the full length of the member 10. Projecting into the outer end and arranged axially of the tubular member 10 is a combustion air supply pipe 18 having its outer end connected to the outer end of the passage 17 by a detachable pipe 19 and its inner end opening to an intermediate portion of the tubular member 10. One

or more spiral vanes 20 are positioned in the pipe 18 adjacent its inner or discharge end. An air supply connection 21 opens to the inner end of the helical passage 17.

- 5 In the outer end of the tubular member 10 is positioned an annular plunger 22 surrounding the air pipe 18 and movable in the member 10 from the outer end of the fuel supply passage 11 inwardly a predetermined distance. The outer 10 end of the member 10 has its upper half cut away and its lower half provided with diametrically opposite horizontal flanges 23, which slidably support reciprocating arms 24 extending laterally from the plunger 22.
- 15 The mechanism for actuating the arms 24 and thereby the plunger 22 comprises a pair of hydraulic cylinders 25 arranged at opposite sides of the tubular member 10, each cylinder containing a piston 26 mounted on a piston rod 27, which 20 extends through the outer end wall of the cylinder and has its outer end connected to the corresponding arm 24. The mechanism for actuating and controlling the operation of the pistons 26 includes a water supply pipe 30 having a control valve 31 therein and leading to one side of a four-way control valve 32, to the opposite side of which a drain pipe 33 is connected. Pipe lines 34 and 35 are connected to the remaining opposite sides of the valve 32, the pipe line 34 being 25 connected to a pipe 36 leading to the outer ends of the cylinders 25 through branches 37 and 38. In the branch 38 is located an adjustable needle valve 39, while the branch 37 is provided with a check valve 40 arranged to permit a fluid flow 30 only from the pipe 36. The pipe 35 divides into equal branches 41, the ends of which are connected to the inner ends of the cylinders 25. The valve 32 may be advantageously connected to suitable automatic valve operating mechanism 35 40 (not shown) which may be adjusted along with the valve 39 to obtain any desired speed of the plunger 22.

With the pistons 26 in the outer ends of the cylinders, the valve 32 is set so that water from 45 the pipe 30 enters the pipe 34 from which it passes into the branch 38, through the needle valve 39 and into the cross pipe 36 through which it enters the outer ends of the cylinders. At the same time water is entering behind the pistons 50 26 any fluid in front of the pistons passes out through the branch pipes 41 into the pipe 35 and through the valve 32 to the drain connection 33. As the pistons complete their forward strokes, the valve 32 is shifted to disconnect the 55 pipe 35 from the drain 33 and connect it to the supply pipe 30. This change in the position of the valve 32 closes the connection between the pipes 30 and 34 and connects the latter to the drain 33. Water then enters the inner ends of the cylinders 25, and any water present behind 60 the pistons 26 passes through the branches of the pipe 36 to the pipe 37 and through the check valve 40 to the pipe 34 and drain 33. With the foregoing operations, the pistons 25 will have a 65 slow forward stroke and a relatively fast return.

In normal operation with the apparatus described, solid fuel is supplied to the hopper 12, preferably in a crushed condition, and delivered from the hopper to the tubular member 10 70 through the port 11 during the return stroke of the plunger 22. During each inward or compression stroke of the plunger, a fuel charge is compressed in the annular space between the air pipe 18 and tubular member 10. During the compression stroke of the plunger 22 an inward move-

ment of the previously compacted fuel mass 55 is also effected in the tubular member 10. A swirling stream of preheated air is discharged from the pipe 18 axially of the compacted tubular mass of fuel and effectively scrubs the exposed inner surface of the fuel mass. Ignition of the fuel is effected in any suitable manner and combustion will continue at a relatively high rate of heat release in the inner portion of the tubular member 10. The radiant and conducted heat 10 from the burning fuel in the inner section of the member 10 gradually raises the temperature of the fuel as it approaches the combustion zone, causing the moisture and volatile combustible gases to be driven off, and coking the fuel. The 15 coking of the fuel mass causes it to swell and become initially tarry and then dry and the straight form of the member 10 causes the fuel mass to resist but not prevent movement and hold its shape against disintegration after passing beyond the inner end of the air pipe 18 until it has burned away from the inside by the flow of air therethrough.

When the apparatus is first put into use, the fuel can be compacted in position around the air 25 pipe 18 by any suitable means for ignition and initial coking. After the apparatus has once been used, a coked tube of fuel, as shown in Fig. 5, will be present in the member 10 and can be directly ignited in any known way.

The cross-sectional area and length of the tubular member 10, the size of the air pipe 18 and the air and fuel supplies are so relatively proportioned that combustion will be completed before the fuel mass can reach the inner end of 35 the member 10. As shown in Figs. 4 and 5, the inner exposed surface of the fuel mass assumes the shape of a flaring zone extending from substantially the inner end of the air pipe to the inner end of the member 10. The speed of the 40 plunger 22 is advantageously regulated in accordance with the rate of consumption of the tubular fuel mass. When the plunger reaches the end of its compression stroke the inner end of the fuel mass will be at approximately the inner 45 end of the member 10, as shown in Fig. 4. During this stroke of the plunger the portion of the fuel mass immediately beyond the inner end of the air pipe tends to expand slightly toward the axis of the chamber, according to the well known 50 pressure conditions found in coking apparatus, as indicated at 51. As the stream of air continues and combustion proceeds, the bulging portion will be rapidly burned away and the inner portion of the fuel mass will acquire the shape shown in 55 Fig. 5. The fuel when coked has a strong structural formation which facilitates longitudinal movement of the portion of the fuel mass located beyond the inner end of the air pipe by the plunger movement.

The stream of air for combustion is regulated to scrub the surface of the burning fuel at a sufficiently high velocity to maintain a high rate of combustion per unit of exposed fuel area, and to burn substantially all of the combustible gases 65 evolved in the combustion chamber. The scrubbing action of the air on the fuel surface is facilitated by the whirling movement effected by the vane 20. The rate of combustion is readily controlled by varying the rate of air discharge from 70 the pipe 18. The rate of fuel supply may be separately controlled by varying the speed and number of strokes of the plunger 22. The normal heat release rate maintained will be sufficient to maintain the temperature in the combustion 75

zone above the fusion temperature of the ash in the fuel and the ash will fuse into molten particles in the combustion chamber. With the axis of the burner arranged horizontally, as shown, the molten particles of ash will be carried out of the inner end of the combustion chamber by gravity and the dragging effect of the products of combustion, and drop into the bottom of the associated heat utilizing device, while the products of combustion will be utilized for heat transfer purposes. The passage of air through the helical passage 11 will provide an effective cooling of the tubular member 10, as well as serving as a convenient source of pre-heated air for the burner.

The fuel burning method and apparatus described are particularly effective for burning solid fuel in a relatively small combustion space, while disposing of the ash content in a manner which will render the products of combustion free from cinders and fly ash.

While in accordance with the provisions of the statutes I have illustrated and described herein the best form of my invention now known to me, those skilled in the art will understand that many changes may be made in the particular form of apparatus disclosed without departing from the spirit of my invention as covered by the claims, and that certain features of my method and apparatus may sometimes be used to advantage without a corresponding use of other features.

I claim:

1. A method of burning solid coking fuel which comprises introducing the fuel into one end of a chamber, compressing the fuel introduced into a tubular mass in the chamber, igniting the tubular mass of fuel, maintaining a stream of air for combustion axially of and scrubbing the exposed inner surface of said burning tubular mass, discharging the heating gases generated from the opposite end of the chamber, and advancing the tubular mass of fuel towards said opposite end of the chamber.

2. A method of burning solid coking fuel which comprises introducing the fuel into one end of an elongated chamber, compressing the fuel introduced into an elongated tubular mass in the chamber, igniting the tubular mass of fuel, maintaining a stream of air for combustion axially of and scrubbing the exposed inner surface of said burning tubular mass and at a velocity sufficient to maintain a high rate of combustion per unit of exposed fuel area and burn substantially all of the combustion gases evolved, discharging the heating gases generated from the opposite end of the chamber, and advancing the tubular mass of fuel towards said opposite end of the chamber.

3. A method of burning solid coking fuel which comprises introducing the fuel into one end of an elongated chamber, compressing the fuel introduced into an elongated tubular mass in the chamber, igniting the tubular mass of fuel, maintaining a stream of air for combustion axially of and scrubbing the exposed inner surface of said burning tubular mass and at a velocity sufficient to maintain a high rate of combustion per unit of exposed fuel area and burn substantially all of the combustible gases evolved, discharging the heating gases generated from the opposite end of the chamber, and progressively advancing the tubular mass of fuel towards the discharge end of the chamber.

4. A method of burning solid coking fuel which comprises periodically introducing the fuel into

one end of an elongated chamber, compressing the fuel introduced into an elongated tubular mass in the chamber, igniting the tubular mass of fuel, maintaining a stream of air for combustion axially of and scrubbing the exposed inner surface of said burning tubular mass and at a velocity sufficient to maintain a high rate of combustion per unit of exposed fuel area and burn substantially all of the combustible gases evolved, discharging the heating gases generated from the opposite end of the chamber, and periodically advancing the tubular mass of fuel towards the discharge end of the chamber.

5. A method of burning solid coking fuel which comprises introducing the fuel in a finely divided form into one end of an elongated chamber, compressing the fuel introduced into an elongated tubular mass in the chamber, igniting the tubular mass of fuel, maintaining a swirling stream of preheated air for combustion axially of and scrubbing the exposed inner surface of said burning tubular mass and at a velocity sufficient to maintain a high rate of combustion per unit of exposed fuel area and burn substantially all of the combustible gases evolved, advancing the tubular mass of fuel towards the opposite end of the chamber, and discharging the heating gases generated from said opposite end of the chamber and utilizing the heating gases for heat transfer purposes.

6. Apparatus for burning solid fuel comprising means forming a fuel compression and combustion chamber, means for supplying solid fuel to said chamber, means in said chamber for compressing the fuel supplied thereto into a tubular mass, and means for introducing a stream of air for combustion axially of and scrubbing the exposed inner surface of said tubular mass.

7. Apparatus for burning solid fuel comprising means forming an elongated fuel compression and combustion chamber, means for supplying solid fuel to one end of said chamber, means in said chamber for compressing the fuel supplied thereto into an elongated tubular mass and advancing previously compacted fuel towards the opposite end of said chamber, and means for introducing a stream of air for combustion axially of and scrubbing the exposed inner surface of said tubular mass and at a velocity sufficient to maintain a high rate of combustion per unit of exposed fuel area and burn substantially all of the combustible gases evolved.

8. Apparatus for burning solid fuel comprising means forming an elongated fuel compression and combustion chamber, means for supplying solid fuel in a finely divided condition to one end of said chamber, means in said chamber for compressing the fuel supplied thereto into an elongated tubular mass and advancing previously compacted fuel towards the opposite end of said chamber, and means for introducing a stream of preheated air for combustion axially of and scrubbing the exposed inner surface of said tubular mass and at a velocity sufficient to maintain a high rate of combustion per unit of exposed fuel area and burn substantially all of the combustible gases evolved.

9. Apparatus for burning solid fuel comprising means forming an elongated fuel compression and combustion chamber, means for supplying solid fuel in a finely divided condition to one end of said chamber, means in said chamber for compressing the fuel supplied thereto into an elongated tubular mass and advancing previously compacted fuel towards the opposite end of said chamber.

- chamber, means for introducing a swirling stream of preheated air for combustion axially of and scrubbing the exposed inner surface of said tubular mass and at a velocity sufficient to maintain a high rate of combustion per unit of exposed fuel area and burn substantially all of the combustible gases evolved, and heat utilizing apparatus arranged to receive heating gases from the opposite end of said chamber.
10. A fuel burner comprising a tubular member having a fuel supply opening adjacent one end and open at its other end for the discharge of heating gases, means for supplying solid fuel to said fuel supply opening, a combustion air supply pipe axially arranged in said tubular member at said one end thereof, a plunger surrounding said air pipe and movable in said tubular member between said one end thereof and the discharge end of said air pipe, and means for reciprocating said plunger in said tubular member to compress fuel entering said fuel supply opening into a tubular mass.
11. A fuel burner comprising an elongated tubular member having a fuel supply opening adjacent one end and open at its other end for the discharge of heating gases, means for supplying solid fuel to said fuel supply opening, a combustion air supply pipe axially arranged in said tubular member at said one end thereof, an annular plunger surrounding said air pipe and movable in said tubular member between said one end thereof and the discharge end of said air pipe, and means for reciprocating said plunger in said tubular member to compress fuel entering said fuel supply opening into a tubular mass and advance previously compacted fuel towards said other end of said tubular member.
12. A fuel burner comprising an elongated tubular member of heat resistant material having a fuel supply opening adjacent one end and open at its other end for the discharge of heating gases, means for supplying solid fuel in a finely divided condition to said fuel supply opening, a combustion air supply pipe axially arranged in said tubular member at said one end thereof, an annular plunger surrounding said air pipe and movable in said tubular member between said one end thereof and the discharge end of said air pipe, means for reciprocating said plunger in said tubular member to compress fuel entering said fuel supply opening into a tubular mass and advance previously compacted fuel towards said other end of said tubular member, a cooling jacket surrounding said tubular member, and means for passing air through said cooling jacket and delivering the preheated air to said air pipe.
13. A method of burning solid coking fuel which comprises compressing the fuel into a tubular mass, igniting the mass of fuel, while maintaining a supply of air thereto and continuing to pass a stream of air for combustion axially of and scrubbing the exposed inner surface of said burning tubular mass, and moving the tubular mass of fuel towards the combustion zone as combustion proceeds.
14. A method of burning solid coking fuel which comprises compressing the fuel into a tubular form in a combustion chamber while advancing a tubular mass of previously compacted burning fuel in said chamber, and passing a stream of air for combustion axially of and scrubbing the exposed inner surface of said tubular mass.

ERVIN G. BAILEY.
